GAS CONTROL SYSTEM AND APPARATUS

George A. Tuck, San Francisco, Calif.

Application November 30, 1931
Serial No. 578,013

3 Claims. (Cl. 158—117.1)

This invention relates generally to systems and apparatus for controlling supply of fuel gas to various appliances, as for example domestic heating furnaces, or hot water heaters. It has 5 particular application to systems of this character in which a pilot burner is utilized for effecting ignition of a primary burner.

It is a general object of the invention to devise 10 a gas control system which will adapt itself to various domestic installations, and which will preclude the possibility of gas being supplied to a primary burner when the pilot burner has become extinguished.

It is a further object of the invention to devise 15 a system and apparatus of the above character having a minimum of working parts, which can be readily installed and adjusted, and which will make use of certain parts now common in domestic heating installations, as for example 20 electrically controlled valves.

Further objects of the invention will appear 25 from the following description in which the preferred embodiment of my invention has been set forth in detail in conjunction with the accompanying drawing. The appended claims, in which the invention is defined, are to be accorded 30 a range of equivalents consistent with the state of the prior art.

Referring to the drawing: 35 Fig. 1 is a diagrammatic view, partly in cross section, illustrating my complete system and apparatus.

Fig. 2 is a plan view, illustrating the relationship 40 between the pilot burner of my apparatus, and a primary burner of a heating appliance.

Referring to Fig. 1 of the drawing, the apparatus shown therein consists of a pilot burner 10 associated with the primary burner 11 of a gas appliance, such as a domestic heating furnace or 45 a hot water heater. A suitable casting 12 serves to support pilot burner 10 and certain other associated parts. The particular form of burner 10 illustrated consists of a tube 13, having its lower portion threaded into casting 12, and having a flame tip 14 secured to its upper end. The passageway 16 through the tube 13, communicates with the bore 17 in the flame tip, and the flame tip is provided with a slot 18 so that a fan-like flame is produced. Gas supply pipe 19 connects 50 with passageway 21 in casting 12, and this passageway in turn is in communication with passageway 16 through the restricted orifice 22. Ports 23 permit introduction and admixture of air into the gas stream.

55 Associated with the pilot burner 10 there is

a thermostatic element 24, preferably in the form of a bimetallic strip 25 bent U-shaped as illustrated. One end of this strip is shown fixed to lug 26, provided on casting 12, while the other end is suitably connected to a flexible motion transmitting member, such as a steel wire 27. Thus in the construction illustrated the free end of bimetallic strip 25 carries a member 28, which is apertured to receive the end of wire 27. Set screw 29 is threaded into member 28, and serves 60 to adjustably grip wire 27.

The parts of the apparatus just described are 65 preferably located within the combustion chamber of a furnace or other gas appliance with which the apparatus is being employed. Certain 70 other parts of the apparatus, to be presently described, are preferably located at some convenient point outside of the combustion chamber. Wire 27 is extended to this other apparatus and in order to properly protect it, it is shown housed 75 within a tube 31. One end of this tube is shown secured to casting 12, by means of fitting 32. An upstanding portion 33 of casting 12 is shown provided with a gas port 34, in communication 80 with gas supply tube 36, through fitting 37. As will be presently explained, gas supplied through tube 36 and port 34 facilitates recycling my system after the pilot burner has become extinguished.

One part of my apparatus, which is preferably 85 located outside of the combustion chamber for primary burner 11, consists of a body 38, which connects with pipe 19, tube 31, and tube 36 through fittings 39, 40, and 41 respectively. Formed within body 38 there is a bore 42, provided with a suitable liner 43, forming a cylinder. Slidably fitted within liner 43, there is a piston 44, which is apertured to receive the extended end of wire 27. Set screw 46, threaded into piston 44, serves to fix the wire to the piston. Formed 90 within body 38 there is also a valve seat 47, one side of which has communication with pipe 19 by way of duct 48, the other side of which has communication with the interior of liner 43 by way of duct 49. A valve member 51 of the needle type, cooperates with seat 47, and it can be controlled by an external knob 52. Body 38 is also provided with another valve seat 53, one side of which communicates with tube 36 through duct 54, and the other side of which communicates with a pipe 56, by way of duct 57. A valve member 58 of the needle type cooperates with seat 53, and this valve member is likewise threaded into body 38 and controlled by external knob 95 100 105 110 59. Passageway 60 serves to establish communication.

cation between the inflow side of seat 53 and the interior of liner 43. Dependent upon the temperature of bimetallic strip 25, piston 44 assumes certain positions with liner 43, as will be presently explained.

In addition to controlling flow of gas through certain passages or ducts within body 38, movements of piston 44 are also utilized for controlling an electrical valve, which in turn controls supply of gas to the primary burner 11. In Fig. 1 I have diagrammatically illustrated a gas control valve 63, which can be of the electrical solenoid type in which the valve member is normally biased towards closed position, but moved to open position by application of electrical current. This valve is indicated as being connected to a gas supply line 64, and to a line 66 supplying the main burner 11. The electrical winding of this valve is connected serially with an electrical circuit indicated generally at 67. A suitable supply of current for this circuit can consist of the secondary of an alternating current step down transformer 68. Likewise serially connected with this circuit, there is a thermostat 69, which is generally located at a remote point, and which is controlled for example by temperature of air in a room or dwelling being heated. Thermostats of this character are well known in the art, and utilize contacts which are opened and closed in accordance with the temperature of air.

Control of circuit 67, by movements of piston 44, is accomplished by contact means which can be constructed as follows:—As illustrated in Fig. 1, an insulating bushing 71 is shown fitted within body 38, and in alignment with the cylinder formed by liner 43. Slidably fitted within bushing 71, there is a plunger 72, the inner end of which forms an electrical contact. A suitable binding post or terminal connector 73 is mounted upon the outer end of bushing 71, and is connected to circuit 67. A compression spring 74 serves to urge plunger 72 inwardly. When piston 44 is moved sufficiently far in one direction, set screw 46 contacts with plunger 72, and since this plunger is connected with binding post 73 through spring 74, then the wire of circuit 67 connected with binding post 73 is grounded through body 38.

Operation of the complete system illustrated in Fig. 1 can be explained briefly as follows:—When in normal operation, with the pilot burner 10 ignited, bimetallic strip 25 is maintained in heated condition, so that its free end is maintained in the position illustrated in dotted lines. Set screw 46 of piston 44 is therefore maintained into contact with plunger 72, so that the electrical circuit 67 for electrically operated valve 63, is completed through the grounded body 38. When in such position, piston 44 permits flow of gas from pipe 56, through ports 60 and 49, through valve seat 47 and thence through pipe 19 to the pilot burner. The size of the pilot burner flame can be adjusted by changing the setting of needle valve member 51. Needle valve member 58 at this time is closed. If the contacts of thermostat 69 are now closed, electrically operated valve 63 is actuated to permit flow of gas to the primary burner 11. If the pilot burner flame becomes extinguished from some cause, as for example an abnormal reduction of gas pressure, or by an abnormal draft, bimetallic strip 25 is permitted to cool so that its free end assumes the position illustrated in Fig. 1 in solid lines. Piston 44 is correspondingly moved to the position likewise illustrated in solid lines, to interrupt communication between ducts 60 and 49,

and thus preventing further flow of gas to the pilot burner through pipe 19. At the same time, set screw 46 moves out of contact with plunger 72 so that the electrical circuit 67 is opened. Opening of this electrical circuit precludes operation of electrically operated valve 63, to again supply gas to the primary burner 11. In the event that the primary burner is ignited when the pilot burner flame becomes extinguished, it will re-ignite the pilot burner flame, before bimetallic strip 25 has had an opportunity to cool. Obviously when piston 44 has moved to the position illustrated in solid lines, no flow of gas can occur to either the pilot or the primary burner, and therefore there can be no danger of an explosion due to accumulation of combustible gas in the combustion chamber. To recycle the system, the operator opens needle valve member 58, to permit gas to flow from port 34, and this gas is then manually ignited to produce a flame to heat bimetallic strip 25. Upon heating of this strip, it is flexed to the position illustrated in dotted lines to again permit flow of gas to the pilot burner, at which time the pilot burner is ignited by the flame from the recycling burner. Following such recycling the operator closes needle valve member 58.

I claim:

1. In a control system, a primary gas burner, a pilot burner associated with the primary burner, a movable valve member for controlling the supply of gas to the pilot burner, thermostatic means cooperably positioned with respect to said pilot burner for actuating said valve member to shut off the supply of the gas to the pilot burner when the flame of the same becomes extinguished, an electrically actuated valve for controlling the supply of gas to the primary burner, an electrical control circuit for said valve, contacts connected with said circuit and positioned to be actuated by movement of said valve member, whereby when said valve member is moved in a direction to interrupt supply of gas to the pilot burner, said contacts are opened to disrupt said electrical circuit, a recycling gas burner cooperating with said pilot burner and said thermostatic means, said recycling burner being arranged to heat said thermostatic means and to likewise ignite the pilot burner, and manually controlled means for supplying gas to said recycling burner.

2. In a control system, a primary gas burner, a pilot burner associated with the primary burner, a movable valve member for controlling the supply of gas to the pilot burner, thermostatic means responsive to the heat of the pilot burner for actuating said valve member to shut off the supply of gas to the pilot burner when the flame of the same becomes extinguished, an electrically operated valve for controlling supply of gas to the primary burner, an electrical control circuit for said valve, contacts connected with said circuit and operable by movement of said valve member, whereby when said valve member is moved in a direction to interrupt supply of gas to the pilot burner, said contacts are opened to disrupt said electrical circuit, a recycling burner cooperating with said pilot burner and said thermostatic means, said recycling burner being arranged to heat said thermostatic means and to likewise ignite the pilot burner, and manually controlled valve means for controlling supply of gas to said recycling burner, said last named valve means, said valve member, and said

contacts, being connected together as a single structural unit.

3. In a control system, a primary gas burner, a casting to be positioned adjacent the primary burner, a thermostatic element carried by the casting, a pilot burner likewise carried by the casting and positioned to ignite the primary burner and to heat the thermostatic element, a recycling burner likewise carried by the casting and positioned to heat the thermostatic element and to ignite the flame of the pilot burner, a movable valve member remote from the primary burner for controlling the supply of gas to the pilot burner, a mechanical connection between the thermostatic element and the valve

member to cause the valve member to be actuated to shut off the supply of gas to the pilot burner when the flame of the pilot burner becomes extinguished, an electrically actuated valve for controlling the supply of gas to the pilot burner, an electrical control circuit for said valve, contacts connected with said circuit and positioned to be actuated by movement of said valve member, whereby when said valve member is moved in a direction to interrupt supply of gas to the pilot burner, said contacts are opened to disrupt said electrical circuit, and manually control means for supplying gas to the recycling burner.
